CASE B.

To all whom it may concern:

Be it known that I, EMIL CRISAND, of New Haven, in the county of New Haven and State of Connecticut, have invented a new Design for Embroidery-Pattern; and I do hereby declare the following, when taken in connection with the accompanying drawings and the letters of reference marked thereon, to be a full, clear, and exact description of the same, and which said drawings constitute part of this specification and represent the design.

This invention relates to a design for embroidery-pattern intended especially for perforated board; and it consists in the peculiar configuration and ornamentation of the motto, as shown in the accompanying illustration.

The motto forming the base of this design

is "Thy Will be Done." The form of the letters composing the several words is clearly shown in the accompanying illustration, the capitals being the principal feature in this part of the design. The ornamentation in this design consists of a border and filling of angular and scroll work, interspersed with crosses and cups as emblems, as shown in the accompanying illustration.

I claim—

The design for embroidery-pattern herein described, consisting of the motto, "Thy Will be Done," in form and ornamentation as shown in the accompanying illustration.

EMIL CRISAND.
